UNITED STATES PATENT OFFICE.

JOHN F. ZAK, OF CHICAGO, ILLINOIS.

DETACHABLE BUTTON.

1,071,855.

Specification of Letters Patent.

Patented Sept. 2, 1913.

Application filed November 12, 1912. Serial No. 730,960.

To all whom it may concern:

Be it known that I, JOHN F. ZAK, a citizen of the United States, residing at Chicago, in the county of Cook and State of Illinois, have invented a new and useful Improvement in Detachable Buttons, of which the following is a specification.

This invention relates to a button and especially to means for securing the button in position upon the fabric, and the invention is especially adapted to military and ornamental buttons, as by means of my invention said buttons can be quickly detached from the fabric for the purpose of polishing or cleaning, and can be readily reinserted in position.

The invention consists of the novel features of construction hereinafter described, pointed out in the claims and shown in the accompanying drawings, in which,

Figure 1 is an inner face view of the button, the parts being shown in locked position. Fig. 2 is a similar view parts being shown in position ready for unlocking. Fig. 3 is a similar view, the button being moved into position for disengagement with a locking disk. Fig. 4 is a sectional view. Fig. 5 is a face view of the locking disk and its ring with the button removed. Fig. 6 is a perspective view of the button detached.

The invention consists of three parts, a button 1, a disk 2, and a split ring 3 movable about the periphery of the disk, the said disk being suitably grooved to receive said ring. The disk is provided with a suitable key-hole slot 4, the head of which is to one side of the center of the disk and with a notch 5, said notch being in radial alinement with the slot 4. The button is provided with a bifurcated shank 6, each member of which is transversely grooved as shown at 7, said grooved portions being adapted to engage respectively the slot 4 and the notch 5.

In use the shank is inserted through the fabric, the ring is turned so that the opening in said ring will register with the notch

5 and the shank members of the button are then brought respectively into registry with the notch and the head of the key-hole slot 4, and the parts are moved relative to each other so as to bring said shank members into the inner end portions of the notch and slot and the ring is then turned to close the entrance to the notch 5. With the exception of the head portion of the slot 4 neither the slot nor the notch are of sufficient width to permit the extreme end portions of the shank members to pass therethrough so that the button cannot become detached except by again turning the ring into the position shown in Figs. 2, 3 and 5 and sliding the shank members into position for withdrawal.

The disk can be formed of the same material as the button and if desired can be in one piece but as shown most clearly in Fig. 4, I have illustrated said disk as being formed of two pieces: an inner face portion A of bone, celluloid or other suitable material and a backing B of metal, these two parts being secured together.

What I claim is:

1. The combination with a button having a bifurcated shank, the end portions of which are transversely grooved, of a disk having a radial notch, and a key-hole slot in alinement with said notch, and a split ring movable upon the periphery of the disk.

2. A device of the kind described comprising a button having a bifurcated shank, the end portions of which are transversely grooved, a disk having a radial notch to receive one of said end portions, and a key-hole slot to receive the other end portion, and a split ring rotatable about said disk and adapted to close the entrance to said notch, as and for the purpose set forth.

JOHN F. ZAK.
